Primary Examiner — Mitchell I. Siegel*(74) Attorney, Agent, or Firm* — Squire Patent Consulting & IP Law LLC; Brendan E. Squire(57) **CLAIM**

The ornamental design for a golf ball carrier, as shown and described.

DESCRIPTION

FIG. 1 is a front perspective view of a golf ball carrier showing my new design;

FIG. 2 is a right side elevation view thereof, the left side elevation view being a mirror image thereof;

FIG. 3 is a rear elevation view thereof;

FIG. 4 is a front elevation view thereof;

FIG. 5 is a top plan view thereof; and,

FIG. 6 is a bottom plan view thereof.

The broken lines shown in the drawings illustrate portions of the golf ball carrier that form no part of the claimed design.
